UNITED STATES PATENT OFFICE

SYLVESTER J. STIVER, OF NEW BETHLEHEM, PENNSYLVANIA

SKATE

Application filed October 12, 1929. Serial No. 399,254.

The present invention relates to skates and the prime object of the invention is to provide a skate with means for propelling the same by a rocking movement of the foot.

Another very important object of the invention resides in the provision of a foot propelled skate of this nature which is simple in its construction, inexpensive to manufacture, strong and durable, compact and convenient in its arrangement of parts, easy to manipulate and thoroughly efficient and reliable in use and operation.

With the above and numerous other objects in view as will appear as the description proceeds, the invention resides in certain novel features of construction, and in the combination and arrangement of parts as will be hereinafter more fully described and claimed.

20 In the drawing:

Figure 1 is a side elevation of a skate embodying the features of my invention.

Figure 2 is a section taken on the line 2—2 of Figure 1.

25 Figure 3 is an enlarged detail section taken longitudinally and vertically through the plate substantially on the line 3—3 of Figure 2,

Figure 4 is a somewhat similar detail section showing the opposite side of the gearing, and

Figure 5 is a vertical transverse section taken substantially on the line 5—5 of Figure 1.

35 Referring to the drawing in detail it will be seen that the numeral 5 denotes a bottom plate formed with an opening 6 adjacent the rear thereof. A bumper 7 is fixed on top of the plate 5 immediately to the rear of the opening 6. A bar 8 is fixed longitudinally under the body plate and has depending substantially V-shaped front and rear portions 9 and 10 respectively.

Front rollers 11 are journaled on an axle 45 12 in the bottom of the portion 9. An axle shaft 13 is journaled in the portion 10 with rollers or wheels 14 fixed to the ends thereof.

To an intermediate portion of the axle shaft 12 there is fixed a gear 15. A shaft 16 is 50 journaled in a bearing 17 of the ball bearing

type carried in the upper forward part of the portion 10 and on this shaft 17 there is a gear 18 meshing with the gear 15, a rack pinion 19 and a ratchet 20.

55 A spring pressed pawl 21 cooperates with the ratchet 20 to allow rotation of the shaft 16 in one direction only. The pawl 21 is carried by the gear 18 which is loose on the shaft 16 while the rack pinion 19 and the ratchet 20 are fixed to the shaft.

60 A rack bar 25 meshes with the rack pinion 9. This rack bar passes through the opening 6 and is held in engagement with the rack gear by means of a roller 26 journaled in a bracket 27 on the bottom of the plate 5. 65 A U-shaped bracket 28 rises from the plate 5 and rockably supports a foot plate 29 with the rear end of which is pivotally engaged as at 30 the upper end of the rack bar 25.

70 The rear end of this rockable foot plate will abut the bumper 7 thus eliminating the downward movement thereof. It will thus be seen that by rocking the foot when the skate is worn the skate may be propelled 75 forwardly by the transmission of intermittent rotation to the gear 18 and the gear 15 through the oscillation of the rack bar.

75 It is thought that the construction, operation, utility and advantages of this invention will now be quite apparent to those skilled in this art without a more detailed description thereof.

The present embodiment of the invention has been described in detail merely for the 80 purposes of exemplification since in actual practice it attains the features of advantage enumerated as desirable in the statement of the invention and the above description.

85 It will be apparent that changes in the details of construction, and in the combination and arrangement of parts may be resorted to without departing from the spirit or scope of the invention as hereinafter claimed or sacrificing any of its advantages.

90 Having thus described my invention, what I claim as new is:

95 A skate comprising a supporting plate, a rockable foot plate mounted on said supporting plate, a longitudinally extending 100

bar secured to the under side of the supporting plate and having depending substantially V-shaped front and rear portions and shaft bearings in the upper forward part of the said rear portion, axle shafts journaled in the bottoms of the V-shaped front and rear portions of said bar, rollers fixed on the said axle shaft, a driving shaft journaled in the said bearings in the upper forward part of the rear V-shaped portion, a driving connection between said driving shaft and the rear axle shaft, said driving connection operable to rotate the axle in only one direction of rotation of the driving shaft, and means operatively connecting the said rockable foot plate to the said driving shaft for rotating the latter in alternate directions upon rocking movement of said foot plate.

20 In testimony whereof I affix my signature.
SYLVESTER J. STIVER.
